UNITED STATES PATENT OFFICE.

KONRAD FRH. VON BASSUS, OF MUNICH, GERMANY.

HARMONIUM.

SPECIFICATION forming part of Letters Patent No. 589,066, dated August 31, 1897.

Application filed March 21, 1896. Serial No. 584,320. (No model.) Patented in Germany March 24, 1895, No. 84,497.

To all whom it may concern.

Be it known that I, KONRAD FRH. VON BAS-
SUS, a citizen of the Empire of Germany, re-
siding at Munich, Bavaria, Germany, have in-
5 ventioned certain new and useful Improvements
in Harmoniums, (patented in Germany March
24, 1895, No. 84,497,) of which the following is
a specification.

My invention relates to an improvement in
10 harmoniums or organs, and particularly to
a combination stop-action for such instru-
ments and means for operating such an ac-
tion.

The main object of my invention is to pro-
15 vide means whereby the performer may
change the timbre or strength of the tone, or
both, simultaneously without the necessity of
removing the hands from the keys.

The invention consists in the features, de-
20 tails of construction, and combination of
parts, which will first be described in con-
nection with the accompanying drawings, and
then particularly pointed out in the claims.

In the drawings, Figure 1 is a horizontal
25 sectional view of a harmonium, taken just be-
low the diaphragm and illustrating one em-
bodiment of my invention; Fig. 2, a detail
transverse sectional view with the diaphragm
and its attached parts removed; Fig. 3, a de-
30 tail front elevation; Fig. 4, a bottom plan
view of the diaphragm, showing the stop-ac-
tions in place thereon; Fig. 5, a view at right
angles to Fig. 4; Figs. 6 to 9, detail views to
be referred to hereinafter, and Fig. 10 a de-
35 tail transverse sectional view showing a part
of the action in side elevation. Fig. 11 is a
detail view showing the manner of connecting
the flaps B⁶ B⁸ and B⁵ B⁷. Fig. 12 is a short-
ened detail view of the apron D.

40 Referring to the drawings, A is a diaphragm
secured in the casing A' of the harmonium
and serving to support the action which is
located on the under side of the same. This
action in the present case comprises the fol-
45 lowing construction:

To the under side of the diaphragm A are
hinged at b, Fig. 4, a series of flaps or valves
B' to B¹¹, inclusive, which serve to control the
50 supply of air under pressure to the various
sets of reeds, these flaps being placed over
openings in the diaphragm A.

To the under side of the diaphragm A and

at suitable points between the various flaps
B are placed shafts C', C², C³, and C⁴, pro-
vided with gudgeons, which are rotatable in 55
lugs or ears c, secured to the under side of
the diaphragm, the shafts C³ and C⁴ having
their axes in line with each other. The shafts
C' and C² are each provided with an arm or
target c' c², for a purpose hereinafter de- 60
scribed, these arms or targets being in the
present instance located at opposite ends of
their respective shafts, as shown in Fig. 4,
and preferably project downward. The dia-
phragm A also carries a pivotally-mounted 65
apron or small board D, provided with gud-
geons mounted rotatably in lugs d, projecting
downward from the under side of the dia-
phragm.

The stop mechanism comprises a series of 70
pulls or stops, which I have indicated by the
reference-letter E, Figs. 3 and 10, with expo-
nents corresponding to those of the reference-
letter B applied to the flaps or valves, in
order that the connections between each pull 75
or stop and its valve may be readily traced.
For brevity, however, the reference-letters
will be used without the exponents as refer-
ring to all the parts of a kind.

Each stop E is connected by a wire e to a 80
lever F, provided with a cam-shoe f, which
bears against the cap of a stud g, passing
through a hole in the diaphragm and con-
nected to or formed integral with a bell-crank
G, pivoted on the underside of the diaphragm, 85
as shown in Fig. 7. These bell-cranks G are
connected to their corresponding flaps by
wires II, the exponents of the reference-let-
ters G, II, and B indicating the respective
connected parts. For instance, the wire II' 90
connects the bell-crank G' and the flap B¹,
the wire II² the bell-crank G² and the flap B²,
and so on.

By the construction described the flaps or
valves may be individually opened by draw- 95
ing out their respective stops or pulls E,
each stop or pull when thus drawn out being
held against accidental inward movement by
the friction between the respective cam-shoe
f and the cap of the corresponding stud g, 100
the flaps being each provided with a leaf-
spring b', whereby when the respective stops
are pushed in the flaps or valves will be closed
by said springs.

In order to permit the flaps or valves to be actuated by mechanism aside from that just described and which will be explained hereinafter, the wires II are attached to their respective flaps in a manner to permit a certain amount of lost motion in the direction of opening the flaps. This is done, preferably, as follows: Each flap is provided with an ear b^2 , having an opening through which its corresponding wire II passes freely, said wire being provided with a nut or nuts k at one side or at each side of said ear, the nut on that side of the ear farthest removed from the respective bell-crank G being located in close contact with said ear, whereas the nut, if any, on the other side of the ear is slightly removed therefrom, whereby, if the flap be opened by means independent of its individual pull-wire, it will be free to move without out its ear actuating the said wire.

The flaps B^5 and B^7 , B^6 and B^8 , it will be noticed, are connected by arms b^3 , each arm being fixed to one of the outer flaps and provided with a hole at the other end, through which passes loosely a stud b^4 , secured to the corresponding adjacent flap, and provided at its free end with a cap arranged out of contact with its arm when the flaps are in their closed position. By this construction each flap of the two pairs B^5 and B^7 , B^6 and B^8 is capable of a limited amount of movement independent of the adjacent flap to which it is connected, while at the same time by opening each flap to a considerable extent the adjacent flap to which it is connected will also be opened to an extent sufficient to allow the air to pass through its opening, thereby permitting two sets of reeds to sound simultaneously by drawing out either one of the two stops to the necessary extent.

In addition to the above-mentioned connection between the flaps B^6 and B^8 the latter flap is also connected to the flap B^{11} by a wire I, so attached to said flaps as to permit a slight amount of lost motion in the same way as described with relation to the manner of attaching the wires II to their respective flaps, whereby when the flap B^{11} is opened, by pulling out its respective pull or stop E^{11} to the full extent, it will also open the flaps B^8 and B^6 , thus permitting three sets of reeds to sound simultaneously.

K' , K^2 , K^3 , and K^4 are knee-levers movably connected to the front of the harmonium or organ casing A', preferably by hinging, as shown in Figs. 1 and 3, said knee-levers being in pairs, the members of each pair being arranged to move toward and from each other. On that side of each lever away from the corresponding lever of its own pair is an arm, lug, or projection k' k^4 , extending approximately at right angles to its respective knee-lever, the said arms, lugs, or projections being arranged to contact with the outward-projecting ends of stickers L' L² L³ L⁴. Each sticker is adapted to move longitudinally, being guided in openings in the casing A' and

in a block or support l' l^2 l^3 l^4 , secured to any suitable fixed part of the instrument. Each sticker, moreover, is normally held outward by a spring device—such, for instance, as the coiled springs m' m^2 m^3 m^4 —surrounding the stickers, as shown in Fig. 1, each spring bearing against a collar n' n^4 , fixed on the respective sticker and also against the block l' l^4 . By this construction each knee-lever is pressed toward the opposite knee-lever of the pair to which it belongs and to such an extent that it will normally stand approximately at right angles to the front of the instrument, but may be swung toward the opposite member of its pair until it is flat against the front of the instrument, one knee-lever K^3 being shown in this closed position in Fig. 1.

The sticker L' is located so that its inner end is opposite and in comparatively close proximity to the target c', whereby when the said sticker is forced inward the said end contacts with the said target and then partly rotates the shaft c'. This shaft is connected by the wires O', P', Q', R', and S' to the flap B^6 , the shaft C⁴, and the flaps B^4 , B^7 , and B^3 , respectively.

The sticker L² in a similar manner operates the shaft C², the latter being connected by wires O², P², Q², R², S², T², and U² to the shaft C⁴ and to the flaps B^2 , B^4 , B^8 , B^7 , B^3 , and B' , respectively.

The sticker L³ is arranged to contact with a target d³, secured to the apron D, while the sticker L⁴ is also arranged to contact with a target d⁴ on the apron, whereby said apron is given a partial rotation, this apron being connected by wires O³ P³ Q³ R³ V³ to the flaps B^8 B^2 B^4 B^{10} B' B^9 B^3 B^7 , respectively. In addition the said apron is also connected by a wire or rod O to two arms c³ c⁴ on the ends of the shafts C³ C⁴, respectively, and, moreover, is connected by a rod or wire H¹² with a bell-crank G¹², operated from the stop E¹² in the same manner as the bell-cranks G' to G¹¹, previously described. Furthermore, the apron D is connected by a rod or wire W³ to the flap B^{11} .

The two rods C³ C⁴ are each connected by wires H¹³ H¹⁴ with bell-crank levers G¹³ G¹⁴, respectively. As these levers are intended to be used for operating the dampers for the base and treble, the construction intervening between them and their individual stops E¹³ E¹⁴ is somewhat modified. This construction will now be described in connection with the treble-forte mechanism, that for the base being the same.

Referring to Fig. 10 of the drawings, it will be seen that the bell-crank G¹³ is connected by a vertical wire g¹³ to one arm of a swinging lever F¹³, fulcrumed at f¹³ and carrying the damper L, which normally rests on the top of the chest M, in which the tongues or reeds N are located, whereby the sound is damped. By the movement of the bell-crank G¹³ the lever F¹³ is swung on its pivot and the damper L lifted, thus accomplishing the forte

expression on the treble of the instrument. To the lever F¹³ is also connected a pull-wire e¹³, which connects said lever to the stop E¹³. By these various connections, as above described, the flaps may be opened singly or in various combinations and the dampers raised at the time when either one set of reeds or various sets of reeds are being used. Moreover, by using the knee-levers various combinations of stops may be made.

The most important feature of the mechanism thus described is the construction and arrangement of the knee-levers in such a manner that the knees of the performer may be inserted each between the two members of one pair of levers and a change can be made from one combination of stops to another without any break in the music and without taking the hands from the keys by merely moving the knee or knees from one side to the other—that is, from the right to the left, or vice versa.

By the employment of two pairs of knee-levers a still greater advantage arises from the fact that a new mode of operation may be introduced—that is, each lever of a pair may be operated to throw a combination in action at the time one of the opposite knee-levers is being used to throw another combination into action, thus producing still a new combination of reeds.

Having thus fully described my invention,

what I claim as new, and desire to secure by Letters Patent, is—

1. In an organ or similar instrument the combination, with a stop-action, of a pair of knee-levers so placed as to admit the knee of the performer between its constituent members, and mechanism connected to the parts of the stop-action and arranged to be actuated by the knee-levers, the operating movement of one lever of the pair being in a direction opposite to that of the operating movement of the other lever of the same pair, substantially as described. 45

2. In an organ or similar instrument, the combination, with a stop-action, of two pairs of knee-levers, each pair being so placed as to admit the knee of the performer between its constituent members, and mechanism connected to the parts of the stop-action and arranged to be actuated by the knee-levers, the operating movement of one lever of each pair being in a direction opposite to that of the operating movement of the other lever of the same pair, substantially as set forth. 50

In testimony that I claim the foregoing as my invention I have signed my name in presence of two subscribing witnesses.

KONRAD FRH. VON BASSUS.
